UNITED STATES PATENT OFFICE.

HENRY JACKSON DAVIS, OF GOOD WATER, ALABAMA, ASSIGNOR OF ONE-FOURTH TO ZACHERIAH D. McCORD AND BENJAMIN A. McCORD, OF SAME PLACE.

PLOW-STOCK.

SPECIFICATION forming part of Letters Patent No. 468,909, dated February 16, 1892.

Application filed November 9, 1891. Serial No. 411,309. (No model.)

To all whom it may concern:

Be it known that I, HENRY JACKSON DAVIS, a citizen of the United States, residing at Good Water, in the county of Coosa and 5 State of Alabama, have invented a new and useful Plow-Stock, of which the following is a specification.

The invention relates to improvements in plows.
10 The object of the present invention is to provide a simple and inexpensive clamp adapted to secure plow-handles and a standard to a beam and capable of enabling a standard to be readily adjusted without removing the 15 parts to regulate the depth of the plow.

The invention consists in the construction and novel combination and arrangement of parts hereinafter fully described, illustrated in the accompanying drawings, and pointed 20 out in the claims hereto appended.

In the drawings, Figure 1 is a perspective view of a plow provided with clamps embodying the invention. Fig. 2 is a sectional view taken longitudinally of the clamp. Fig. 3 is 25 a similar view taken transversely of the clamp. Fig. 4 is a detail perspective view of one of the clamps.

Like numerals of reference indicate like parts in all the figures of the drawings.
30 11 designate clamps constructed of suitable metal and arranged on opposite sides of a plow-beam 2 and attached to the same by bolts 3 and adapted to secure to the beam plow-handles 4 and a standard 5 and to enable the latter to be readily adjusted to regulate the depth of the cut of the plow. Each clamp is provided with an inclined way or 35 socket 6 to receive a plow-handle and has flanges 7 arranged on opposite sides of the 40 way or socket and is provided with a curved way or socket 8 to receive one side 9 of a plow-standard. The flanges 7 are provided with perforations to receive the bolts for securing the clamps to the beam and have integral 45 segmental extensions 10 to increase the length of a curved way or socket 8. The handle-bars 4 have their lower ends recessed on their inner faces at 11 to permit the passage and adjustment of the sides of the standard and 50 are engaged by points 12, formed integral with the clamps and arranged on the inner faces of the same. The standard is composed of the two sides 9, which are parallel at their

upper ends and form a continuous curve in order to move freely in the curved ways or 55 sockets and are adjusted longitudinally by loosening the bolts 3 and do not necessitate the removal of the clamps.

It will be seen that the clamps are simple and comparatively inexpensive in construction and secure both the handle-bars and the standard to the plow-beam, and that they are capable of preventing the handles splitting and of permitting the standard to be readily 60 adjusted.

From the foregoing description and the accompanying drawings the construction, operation, and advantages of the invention will be readily understood.

What I claim is—

1. The combination, with a plow-beam, plow-handles, and a standard composed of two sides, of a clamp bolted to the beam and provided with inclined ways or sockets to receive the plow-handles and having ways or 75 sockets arranged at an angle to the other sockets and adapted for the reception of the sides of the standard, substantially as described.

2. The combination, with a plow-beam, plow-handles, and a standard composed of curved 80 sides, of clamps secured to the beam and provided with an inclined socket and having flanges arranged on opposite sides of the socket and provided with a curved socket arranged at an angle to the handle-socket to receive a side of the standard, substantially as 85 described.

3. The combination, with a plow-beam, plow-handles provided with recesses near their lower ends, and a standard composed of curved 90 sides, of clamps comprising inclined sockets to receive the handles, flanges and segmental extensions for the same, arranged on opposite sides of the handle-socket, curved sockets arranged at an angle to the inclined sockets to 95 receive the sides of the standard, and points arranged on the inner face of the clamps to engage the handles, substantially as described.

In testimony that I claim the foregoing as my own I have hereto affixed my signature in 100 the presence of two witnesses.

HENRY JACKSON DAVIS.
